FOLDABLE PAPER FIGURINE

Kathleen M. Spagnolo, 1 Recard Lane, Alexandria, Va.

Filed Oct. 7, 1959, Ser. No. 57,845

Term of patent 7 years

(Cl. D29—23)

Fig. 1.

Figure 1 is a plan view of a foldable paper figurine embodying my new design,

Figure 2 is a side elevational view of the device illustrated in Figure 1 showing the same in assembled condition, and

Figure 3 is a front elevational view of Figure 2.

I claim:

The ornamental design for a foldable paper figurine, as shown.
